UNITED STATES PATENT OFFICE.

DAVID R. JOHNSON, OF MILWAUKEE, WISCONSIN.

COFFIN.

SPECIFICATION forming part of Letters Patent No. 243,913, dated July 5, 1881.

Application filed April 25, 1881. (Model.)

To all whom it may concern:

Be it known that I, DAVID R. JOHNSON, of Milwaukee, in the county of Milwaukee, and in the State of Wisconsin, have invented certain new and useful Improvements in Coffins; and I do hereby declare that the following is a full, clear, and exact description thereof.

My invention relates to improvements in coffin-lids, whereby they may be constructed of narrow or refuse lumber, and to surpass in utility and appearance those made of wide or more costly material.

In the drawings, Figure 1 is an under-side view of my device, showing its peculiarities of construction. Fig. 2 is a top view; and Fig. 3, a cross-section on line *x x*, Fig. 2.

Heretofore, in the manufacture of coffin-lids, it has been customary to employ lumber of the whole width of the lid, which renders the same more expensive and heavier than necessary, and to avoid this is the object of my present invention.

In putting up a lid after my invention, I first form the skeleton A of narrow lumber—say two and seven-eighths inches in width and five-eighths inch in thickness. This I make preferably in six pieces, uniting them in any ordinary manner, as by tonguing and grooving, or by doweling. I next prepare the molding B, of about one and seven-eighths inch in width and seven-eighths of an inch thick, in the same manner, and secure it upon the skeleton A in any suitable manner, as shown in Fig. 3. The proportions may be varied to suit the taste, and, of course, due regard for symmetry should be shown in putting the parts together. I next prepare the stiles G, fashioned

from narrow lumber, each conforming along its outer edge to the shape of the skeleton and molding, and having a straight inner edge, except where it is cut out to expose the face of the corpse at F. To unite the stiles I use three wedge-shaped rails, D E I, of different width, which I insert between the edges of the stiles and secure in place in any suitable manner, the rail D at the foot of the lid being the longest and of least width, the rail E, the upper edge of which forms part of the border below the face-opening, being wider and having less taper, and the rail I still wider and forming part of the border about and above the face. When the stiles have thus been secured together, to complete the lid a panel, C, is planted over the opening between the stiles, and then the lid proper is secured to its molding B, which, in turn, is secured to the skeleton A, and a face-plate, H, is removably secured above the face-opening.

The lid thus made is stronger for all practical purposes than one made of solid lumber, is much lighter and cheaper, and is far more finished in appearance.

I claim as my invention—

In a coffin-lid, the narrow stiles G G, in combination with rails D E I, panel C, and a skeleton, A, and molding B, as set forth.

In testimony that I claim the foregoing I have hereunto set my hand this 7th day of April, 1881.

DAVID R. JOHNSON.
